EMERGENCY WARNING LAMP

Herbert R. Dover, Chicago, Ill.

Application October 22, 1956, Serial No. 43,437

Term of patent 14 years

(Cl. D72—1)

Fig. 1

Fig. 3

Fig. 1 is a top plan view of an emergency warning lamp showing my new design

Fig. 2 is an elevational view thereof from the front; and

Fig. 3 is a view similar to Fig. 2 but taken at 90° thereto.

I claim:

The ornamental design for an emergency warning lamp, substantially as shown.
